SUCTION NOZZLE

Gustaf Erik Björkman, Saltsjö-Nacka, Sweden,
assignor to Electrolux Corporation, Dover, Del.,
a corporation of Delaware

Application March 3, 1936, Serial No. 66,834
In Germany March 5, 1935

3 Claims. (Cl. 15—155)

My invention relates to suction nozzles for use in connection with vacuum cleaners, and more particularly to a suction nozzle which is adapted for removing dirt from corners and other more or less inaccessible locations.

The manner in which I attain this object, as well as further objects and advantages of my invention, will be apparent from the following description considered in connection with the accompanying drawing which forms a part of the specification and of which:

Fig. 1 is a front view, partially in cross-section, of a nozzle embodying my invention;

Fig. 2 is a cross-sectional view taken on the line 2—2 of Fig. 1; and

Fig. 3 is a bottom view of the nozzle shown in Figs. 1 and 2.

Referring more particularly to Figs. 1 through 3, reference character 10 designates a suction nozzle including parallel elongated front and rear walls 11 and 12, respectively. These walls are joined at their ends by means of end walls 13. Walls 11, 12, and 13 define an elongated hollow body to which is connected a tubular member 14 adapted to receive a conduit leading to a source of suction, such as a vacuum cleaner unit. Member 14, as shown, extends obliquely from the rear of the nozzle 10.

The lower edges of walls 11 and 12 constitute nozzle lips bounding a lower elongated opening into the hollow body. This opening is partially closed by means of a plate 15 which extends the entire length of the opening between end walls 13 and extends from the rear wall 12 to closely adjacent the front wall 11, leaving a narrow elongated suction opening 16 immediately adjacent to the forward wall 11. Plate 15 may be secured in place by any suitable means, such as screws 17 which have threaded engagement with the nozzle body. It will be noted that the lip formed by forward wall 11 is slightly lower than the lip formed by rear wall 12. Plate 15 is preferably formed with an offset as is shown at 18, in order that its opposite sides may be at substantially the same level as the respective lips. Also, the forward edge of plate 15 bounding the opening 16 is preferably formed as a portion of an arc, as is shown in Fig. 3 in order that the opening 16 may be wider at its central part than at its ends. This is desirable in order to equalize the suction along the length of the suction opening 16, inasmuch as it would normally be greater at the center due to its proximity to the tubular member 14 which is connected to the source of suction.

End walls 13 have portions 19 depending below the lips of both walls 11 and 12. The lower faces 20 of portions 19, which are adapted to contact the surface undergoing cleaning, are rounded as is clearly shown in Fig. 2. As shown, the ends of portions 19 adjacent to forward wall 11 have a larger radius of curvature than the other ends of portions 19. The suction opening 16 is located off-center with respect to the centers of curvature of faces 20, whereby rocking the nozzle on these faces 20 causes suction opening 16 to be brought closer to or removed farther from the surface undergoing cleaning.

The operation of the above described device will be largely apparent from the above description. When tubular member 14 is connected to a source of suction, air is drawn in through suction opening 16 and, if the tool is passed over a dusty surface, dust is entrained with this air. Due to the fact that the suction opening 16 is located immediately adjacent to the forward wall 11 and entirely to one side of the center line of the nozzle, the suction will be strongly concentrated adjacent to forward wall 11. Consequently, if the nozzle is placed against, for instance, a baseboard, the suction will be strongly concentrated at the corner formed by the floor and the baseboard. With an ordinary type of nozzle, no such concentration of suction takes place with the result that much of the dirt deposited in the corner is not removed.

By rocking the nozzle on the curved faces 20, the proximity of the suction opening 16 to the surface undergoing cleaning may be varied and hence, the degree of suction applied to the surface may be varied. For instance, if it is desired to remove small heavy objects, such as grains of sand, this may best be done by rocking the nozzle so that the opening 16 is very close to the surface. On the other hand, larger but lighter objects may be picked up by the nozzle with the opening 16 spaced a greater distance from the surface.

While I have shown and described a more or less specific embodiment of my invention, it is to be understood that this has been done for purposes of illustration only and the scope thereof is to be limited only by the appended claims viewed in the light of the prior art.

What I claim is:

1. In a suction nozzle for cleaning a surface, means including a pair of longitudinally extending side walls and a pair of transversely extending end walls defining an elongated hollow nozzle body, and means for connecting said hollow

- body to a source of suction, said hollow body being formed with an elongated suction opening disposed between said end walls, said end walls having rounded bottom surface contacting portions 5 depending below said side walls, said suction opening being off-center with respect to said rounded portions whereby the distance between said suction opening and the surface is variable by rocking said nozzle on said rounded portions.
- 10 2. In a suction nozzle for cleaning a surface, means including a pair of longitudinally extending side walls and a pair of transversely extending end walls defining an elongated hollow nozzle body, and means for connecting said hollow body to a source of suction, said hollow body being formed with a narrow elongated suction opening immediately adjacent to one of said side walls, said end walls extending below said side walls and having curved surface contacting faces 15 adjacent to the ends of said suction opening, said suction opening being off-center with respect to said curved faces whereby the distance between said suction opening and the surface is variable by rocking said nozzle on said rounded faces.
- 20

3. In a suction nozzle, a hollow body including longitudinally extending straight forward and rear walls and transversely extending end walls, the lower edge of the forward wall being narrow and constituting a straight forward lip of the 5 nozzle, and an imperforate plate member extending from the rear wall to adjacent to the forward wall to define at the front portion of said nozzle a narrow elongated suction opening bounded on one side by said narrow lip and on 10 the other by the edge of said plate member, said end walls being convex downwardly and having their lowest portions spaced rearwardly of said opening, said end walls projecting below said plate member and said forward and rear walls to 15 provide supporting rocker surfaces extending at right angles to the narrow suction opening to normally maintain both said forward lip and said plate member spaced above the surface being cleaned. 20

GUSTAF ERIK BJÖRKMAN.
